MOVABLE FORM FOR DAMS OR THE LIKE

John D. Jessen, O'Hara Township, Allegheny County, Pa., assignor to Blaw-Knox Company, Blawnox, Pa., a corporation of New Jersey

Application October 22, 1938, Serial No. 236,503

7 Claims. (Cl. 25—131)

This invention relates to a form for making poured concrete structures or the like, and, in particular to a form for the construction of inclined walls such as the deck slabs of a dam of the Amburseen type.

Considerable difficulty has been experienced heretofore in handling the form for the lower face of an inclined wall or slab section, particularly when the slab is to be cast at considerable heights above the ground level as in the case of dam construction. The difficulty encountered resides largely in the fact that after the casting of a slab section, the form for the lower face thereof is supported beneath the finished section in a position somewhat inaccessible to workmen on the upper face of the slab. I have invented a novel form and method of handling it which entirely obviate the difficulties encountered heretofore and greatly simplify the movement of a form from one of its successive positions to the next as the slab sections are cast.

A preferred embodiment of the invention comprises a form panel extending between spaced buttresses on which the finished slabs rest. 25 Framing members supporting the panel extend upwardly thereabove to a cross beam adapted to travel up the inclined faces of two adjacent buttresses. A counterbalance secured to the panel is effective to hold the latter in inclined position 30 when the lower portion is freed from a completed slab section and the entire panel is suspended from the cross beam for traveling movement upwardly along the buttresses. This embodiment of the invention and a preferred method of utilizing it will be described in detail herebelow with reference to the accompanying drawings. In the drawings:

Fig. 1 is a sectional view taken through the form of my invention along the plane midway between adjacent buttresses and parallel thereto;

Fig. 2 is a sectional view taken substantially along lines II—II of Fig. 1;

Fig. 3 is a view partly in section, partly in elevation, taken substantially along lines III—III of Fig. 1 and showing the form for the lower face of the slab; and

Fig. 4 is a partial elevation such as might be projected from Fig. 1 onto the plane indicated by the lines IV—IV thereof.

Referring now in detail to the drawings, a dam of the Amburseen type comprises spaced buttresses 10 and 11 of triangular form having inclined faces 12 and laterally projecting shoulders or faces 13. Deck slabs 14 extend between the buttresses, being cast in place upon the faces 13.

The slabs 14 are cast by the aid of a slip form indicated generally at 15 and comprising upper and lower panels 16 and 17.

The upper panel 16 comprises cross beams 18 bridging the space between adjacent buttresses 5 and provided with wheels 19 adapted to travel up the faces 12 of the buttresses. Stringers 20 are secured to the beams 18 at right angles thereto and support a form plate 21. Trusses 22 are secured to the beams 18 to resist deflection thereof. 10 The entire form is held in position on the inclined faces of the buttresses by cleats 23 secured by anchor bolts 24 to the buttresses.

The bottom form or panel 17 is composed of cross beams 25 to which stringers 26 extending 15 at right angles thereto are secured. A form plate 27 is carried on the stringers 26. The form 17 includes adjustable side sections 28 capable of movement inwardly or outwardly along the beams 25 to compensate for minor variations in the side 20 faces of the buttresses.

Tie rods 29 extend between the panel 16 and the panel 17. Each rod is composed of a middle section 30, an upper section 31, and a lower section 32. The several sections are connected by 25 cone nuts 33. As illustrated, the tie rods are provided with holding nuts which bear on cross plates extending between the members comprising the beams 18 and 25.

As best shown in Fig. 3, the stringers 26 forming part of the panel 17 extend upwardly above the upper edge of the form plate 21. The upper ends of these stringers are secured to a cross beam 34 extending between adjacent buttresses and provided with wheels 35 adapted to travel 35 upwardly along the inclined shoulders or lateral faces 13 thereof. The beam 34 with its wheels 35 provides a pivotal support for the panel 17 when the latter is freed for movement upwardly along the buttresses.

A counter-balancing frame comprises members 36 extending downwardly and outwardly, and beams 37 extending outwardly from opposite ends of the stringers 26. The outward ends of the members 36 and the beams 37 are rigidly connected and a counter-balance 38 is disposed on the supporting framework thus provided. Planking may also be laid across the beam 37 as shown at 39 to provide a working platform below the panel 17. The counter-weight 38 is so designed 50 as to hold the panel 17 in inclined position when the latter is free from the adjacent deck slab and is supported exclusively from the cross beam 34. The weights of the various parts are preferably such that, when so suspended, the panel 17 55

swings slightly away from the lower surface of the previously cast slab section.

The method of employing the invention will now be explained, assuming that the parts are in the position shown in Fig. 1 and that the slab 14 shown in the lower portion thereof has already been cast. With the parts in the positions shown, concrete is poured between the panels 16 and 17 to form a slab section, the upper edge of which is indicated at 14'. As shown in Fig. 1, the abutting surfaces of adjacent slab sections are alternately horizontal and normal to the lateral faces of the slabs. When the slab section 14' has been completed, the tie rod sections 31 are unscrewed from the cone nuts 33 which, with the rod sections 30, remain embedded in the slab section. The panel 16 together with its supporting beams and trusses may then be hoisted upwardly along the buttresses, the wheels 19 traveling along the faces 12 thereof. When the panel 16 has been raised into position for casting the next slab, the cleats 23 are relocated to hold the panel in its advanced position. The rod sections 32 are then unscrewed from the cone nuts 33 embedded in the lower face 25 of the slab section 14'. This leaves the panel 17, its supporting framework and the counter-balance suspended solely from the cross beam 34. Limited tilting movement of the latter is permitted on the axles of the wheels 35. As stated, the counterbalance is of such weight relative to the other parts of the panel 17 that the whole structure swings slightly away from the under surface of the slab 14'. The beam 34 may then be hoisted by suitable cables so that it and the entire form 30 structure travels upwardly along the faces 13 of the buttresses, the wheels 35 rolling thereon. When the panel 17 has been raised to the proper position for the casting of the next succeeding slab, the tie bolt sections 31 and 32 are connected by new cone nuts 33 and central rod sections 30 and the entire form is then ready for a further pouring operation. The cycle described is repeated until all the sections of the deck slabs between two adjacent buttresses have been completed.

The procedure described above may be reversed to advantage, i. e., panel 17 may be moved first and panel 16 afterwards. This latter method requires that panel 17 be held, after being raised, by means of cables or otherwise, pending the subsequent raising of panel 16.

It will be apparent from the foregoing description that the invention provides a novel form of construction which can readily be moved from one position to another in the pouring of successive slab sections. The movement of the bottom panel 17 away from the lower surface of the previously cast section is just sufficient to provide easy clearance. The movement of the form from 55 pouring to transporting position is thus relatively slight. While the construction of the bottom panel or form according to the invention is relatively simple and inexpensive, a substantial advantage is derived therefrom in the ease and readiness with which the panel may be advanced upwardly along the buttresses. The saving in the time required for advancing the form, which is made possible by the invention, greatly expedites the erection of structures having inclined walls 60 such as the deck slabs of an Ambursen type dam.

While the invention has been described herein with particular reference to the latter, it may also be employed on other structures where similar problems are encountered.

Although I have illustrated here but a preferred embodiment of the invention, changes in the structure and procedure disclosed may be made without departing from the spirit of the invention or the scope of the appended claims.

I claim:

1. A form for the casting of a slab extending between spaced buttresses and resting on inclined faces thereof comprising a panel adapted to extend between said buttresses, a beam extending between said buttresses adjacent the upper edge 15 of the panel, said panel being secured to the beam, and a counterbalance adapted to hold said panel substantially in its normal inclined position when suspended from said beam.

2. A form for the casting of a slab extending 20 between spaced buttresses and resting on inclined faces thereof comprising a panel adapted to extend between said buttresses, means adjacent the upper edge of said panel adapted to engage said faces to support the panel thereon, and a counter-balance effective to hold said panel substantially in its normal position when supported exclusively by said means.

3. A form for the casting of successive slab sections resting on the inclined faces of spaced buttresses, said form comprising a panel adapted to extend between said buttresses, means adjacent the upper edge of said panel adapted to engage said buttresses for supporting said panel thereon, and a counter-balance effective to hold said panel substantially in its normal, inclined position when freely suspended from said means.

4. Supporting means for an inclined form on which are cast successive slab sections resting on inclined faces of spaced buttresses, said means comprising a suspension adjacent the upper edge of the form adapted to engage said buttresses, and a counter-balance effective to hold said form in inclined position when it swings freely on said suspension.

5. A form for the casting of successive slab sections resting on the inclined faces of spaced buttresses, said form comprising a panel adapted to extend between said buttresses, stringers extending beyond said panel, a cross beam adapted to be tiltably supported on said faces to which said stringers are secured, and a counter-balance holding said panel in inclined position when swinging freely from said beam.

6. A form for the casting of successive slab sections resting on the inclined faces of spaced buttresses, said form comprising a panel adapted to extend between said buttresses, stringers extending beyond said panel, a cross beam having wheels thereon adapted to travel along said faces, said 60 stringers being secured to said beam, and a counter-balance holding said panel in inclined position when swinging freely from said beam.

7. A form for the casting of an inclined slab extending between spaced buttresses, said form 65 comprising a panel adapted to extend between said buttresses and a framework carrying a counterweight so disposed that the form when suspended will remain in inclined position.
